[57] CLAIM

We claim the ornamental design for a plastic bottle including a grip portion, as shown and described.

DESCRIPTION

FIG. 1 is a side elevation view of the front side of a plastic bottle including a grip portion in accordance with the present invention.

FIG. 2 is a side elevation of the right side of the plastic bottle shown in FIG. 1, the left side being a mirror image thereof.

FIG. 3 is a side elevation of the back side of the plastic bottle shown in FIGS. 1 and 2.

FIG. 4 is a bottom plan view.

FIG. 5 is a top plan view of the plastic bottle shown in the prior figures.

FIG. 6 is a perspective view of the plastic bottle shown in the prior figures, showing the back and right sides; and,

FIG. 7 is a dead section of the plastic bottle shown in the prior figures, the section being taken along line 7—7 from FIG. 1.

The broken lines shown in FIG. 4 are for illustrative purposes only and do not form part of the claimed design.
